ATTORNEYS

UNITED STATES PATENT OFFICE.

EDWARD CLAYTON COLEMAN, OF HAMMOND, LOUISIANA.

WRENCH.

1,415,867.

Specification of Letters Patent. Patented May 16, 1922.

Application filed November 2, 1921. Serial No. 512,268.

To all whom it may concern:

Be it known that I, EDWARD CLAYTON COLEMAN, a citizen of the United States, and a resident of Hammond, in the parish 5 of Tangipahoa and State of Louisiana, have invented certain new and useful Improvements in Wrenches, of which the following is a specification.

My invention relates to wrenches and the 10 purpose of my invention is the provision of a wrench including a stationary jaw and a pivoted jaw, the former being constructed to accommodate nuts of various sizes and shapes, with the latter adjustable to 15 co-operate with the stationary jaw in effectively gripping a nut so that when the wrench is actuated a turning of the nut is effected.

I will describe one form of wrench embodying my invention, and will then point 20 out the novel features thereof in claim.

In the accompanying drawing:

Figure 1 is a view showing in perspective one form of wrench embodying my invention. 25

Figure 2 is a view showing the wrench in side elevation and in applied position with respect to a nut.

Figure 3 is a handle end elevation of the 30 wrench shown in the preceding views.

Similar reference characters refer to similar parts in each of the views.

Referring specifically to the drawing, my invention in its present embodiment comprises a stationary jaw J of U-shape formation and having the free ends thereof rabbed to accommodate plates P and to which such plates are riveted or otherwise secured so that they span the ends of the jaw. J' 35 designates a pivoted jaw formed on one end of a shank S which extends through the slot provided between the plates P. At the junction of the jaw J' and the shank S an ear E is formed provided with an opening 40 through which a pivot pin N extends. The latter is fitted within pivoted ears 15 formed on the plates P, and by this arrangement it will be clear that the shank S and the jaw J' are supported for pivotal movement upon 45 the stationary jaw J. The outer end of the shank S is enlarged to provide a handle H

which is adapted to be gripped in operating the wrench.

As clearly shown in Figure 2, the jaw J' is relatively wide as compared to the width 55 of the shank S, and its working surface is serrated or formed with teeth 16 for the purpose of pivotally gripping a nut disposed within the stationary jaw J. The jaw J' is normally urged inwardly with respect 60 to the jaw J by means of a leaf spring R secured to the shank S at one end by a screw 17 and bent outwardly from the shank so that its opposite end bears against the inner side of one end of the stationary jaw 65 J. In the operation of the wrench, the stationary jaw J is arranged to surround the nut in the manner shown in Figure 2, the pivoted jaw J' being swung outwardly against the tension of the spring R so as to 70 allow the ready insertion of the nut into the stationary jaw. When the wrench has been properly associated with the nut, the jaw J' is released so that the spring acts to move the jaw into contact with one face of the 75 nut. By gripping the handle H, and drawing the latter in a clockwise direction as when viewed in Figure 2, it will be clear that the pivoted jaw is forced inwardly against the nut so that the two jaws co- 80 operate to effectively grip the latter when turning the wrench.

By virtue of the size and contour of the stationary jaw, and the pivotal mounting of the movable jaw, it will be manifest that the 85 wrench will accommodate and operate nuts of different sizes and contours. Furthermore, the mounting of the pivoted jaw allows of the oscillation of the wrench, with the pivoted jaw disengaging the nut with 90 each retrograde movement so that the necessity of continuously rotating is eliminated.

Although I have herein shown and described only one form of wrench embodying my invention, it is to be understood that 95 various changes and modifications may be made herein without departing from the spirit of the invention or the spirit and scope of the appended claim.

What I claim is:

100 A wrench comprising a U-shaped stationary jaw, plates spanning and secured to the

free ends of the stationary jaw, a shank operating between and pivotally secured to the plates, a jaw fixed to the inner end of the shank and disposed wholly within the stationary jaw, a handle integral with the outer end of the shank for operating the jaw carried thereby, and a bent blade spring

having one end secured to the shank exteriorly of the stationary jaw and having its other end slidably engaging the stationary jaw between the plates whereby said spring urges the jaw carried by the shank inwardly of the stationary jaw.

EDWARD CLAYTON COLEMAN.
